UNITED STATES PATENT OFFICE.

ARTHUR HENRY VAN DUZEE, OF LEAVENWORTH, KANSAS.

CENTRIFUGAL SEPARATOR.

SPECIFICATION forming part of Letters Patent No. 325,288, dated September 1, 1885.

Application filed August 11, 1884. (No model.)

To all whom it may concern:

Be it known that I, ARTHUR HENRY VAN DUZEE, a citizen of the United States, and a resident of Leavenworth, in the county of 5 Leavenworth, in the State of Kansas, have invented certain new and useful Improvements in Centrifugal Separators, of which the following specification is a full, clear, and exact description, reference being also had to the accompanying drawings, in which—

Figure 1 is a longitudinal vertical section in the plane of the dotted line x x , Fig. 5. Fig. 2 is a detached perspective view of a section of the conveyer-valves. Figs. 3 and 4 are details of the combined tail-supporting box and oil-catching chamber or hood. Fig. 5 is a cross-sectional view on the line y y of Fig. 1. Fig. 6 is an elevation of the feed end of the machine. Fig. 7 is a sectional detail of the 15 main shaft and one of its bearings. Fig. 8 is a top view of one end of the machine, a part of the frame and case being shown cut away to exhibit the gearing beneath.

A' is the outer casing or frame, through the 20 length of which the main driving-shaft B passes, and having a hopper-bottom, A^2 , in which two screw-conveyers, C' C^2 , are arranged to run side by side, as shown in Figs. 1 and 5.

Upon the top of the wall E , which divides 25 the conveyers C' C^2 , is secured a rod, a , around which one end of each of a series of valves, F , is bent, each valve being thus hinged to the rod a , so that it can be turned over to either side to rest by its upper end upon either of 30 the sides of the hopper-bottom A^2 , to cause the material falling from the reel to be guided entirely into one or a portion into each of the conveyers C' C^2 . By this simple means the material may be cut off at any point and guided 35 into the conveyers, as required.

Upon the shaft B , inside of the casing A' , are secured "spiders" or circular beater-supports G' G^2 , having inclined beater-strips b , the strips being parallel with each other and 40 with the shaft B , the whole thus forming a beater-cylinder, as shown. The spiders G' G^2 are formed in two equal semicircular sections and clamped together at the hubs G^3 and at the periphery, so that they can be attached to 45 the shaft B at any point. The beater-cylinder may thus be attached without the use of key-seats, set-screws, or other such means,

which weaken the shaft and render it liable to spring out of line. By this manner of attachment, however, no tendency to spring exists in the shaft. 55

Surrounding the beater-cylinder is a bolted-cloth-covered reel consisting of a cast-iron head-disk, H' , and tail-disk H^2 , and connecting-ribs H^3 . 60

The head-disk H' is provided with an outwardly-projecting central bearing-ring, H^4 , fitting through the wooden head end of the casing A' , and having a gear, I' , cast upon the outer face of this projecting bearing and adapted to engage with a pinion, I^2 , on a shaft, I^3 , on the casing A' . 65

The tail-disk H^2 is provided at its center with an outwardly-projecting hollow stud, K' , fitting into a box or collar, K^2 , the latter supported by set-screws d' d^2 in a shell or sleeve, K^3 . This sleeve is supported by a stud, K^4 , in a bracket, K^5 , on a bridge-tree, K^6 , across the tail end of the frame A' . 70

The tail end of the shaft B passes out through the stud K' , (which is made large enough so that the shaft does not touch it,) and is supported in the sleeve K^3 by a box or collar, K^7 , and set-screws d^3 d^4 , similar to the collar K^2 and set-screws d' d^2 . 75

The stud K^4 is adapted to be adjusted higher and lower in the bracket K^5 by a set-screw, K^8 , so that the shaft B and reel H' H^2 H^3 may be adjusted higher or lower, and by means of the set-screws d' d^2 and d^3 d^4 the reel and shaft 80 may be adjusted laterally, independently of each other. By this means the reel and shaft may be easily adjusted without stopping the machine or removing any of the parts.

K^9 is a hand-hole, through which the adjusting-screw K^8 can be reached and operated. 85

The sleeve or shell K^3 is provided in its lower part with a depressed channel, m' , running downward and outward to form a conduit to convey the oil that drips from the 90 bearings or collars out over a lip, m^2 , away from the machine, and prevent it from running in and mingling with the flour or tailings. The inner edges, m^3 , of this shell are bent inward toward the shaft B to form a lip 95 to retain the oil, &c., and turn it outward and cause it to flow down the channel. 100

The ribs H^3 are formed of sections of angle or L iron, set as shown, and filled on the out-

side with angular wooden strips *e*, to which the bolting-cloth is tacked. The head and tail disks *H' H²* are formed on their outer rims with as many flat sections as there are ribs *H³*, (in the drawings eight,) and on each of these flat sections, between each pair of the ribs *H³*, a wooden strip, *g*, is secured, to which the bolting-cloth is tacked. Just beneath these wooden strips *g*, and parallel therewith, the tail-disk *H²*, small slots *h* are formed, through which the tailings escape into the tail-discharge *E'*.

The outer periphery of the tail-disk *H²* is formed with a lip or flange, *i*, fitting and running in a partition, *L*, dividing the reel-chamber from the discharge-chamber, so that none of the fine material which passes through the cloth on the reel will escape into the tailings.

The interior of the central part of the head-disk *H'*, inside the gear, is filled with a stationary disk, *M'*, attached by a bracket, *M²*, or other means to the bridge-tree which supports the shaft-bearing. The inner surface of this disk *M'* is provided with a wooden ring, *N'*, having a groove, *n'*, in its outer face, in which a cylindrical flange, *n²*, projecting inward from the face of the head *H'*, runs, the whole thus forming a packing between the heads *H'* and *M'* to prevent the escape of the fine meal from the reel.

Wearing-blocks *t t*, of brass or other suitable substance, will be set into the wood of the casing *A'*, against which the projecting ring *H⁴* on the head *H'* runs, so that the revolving reel will not come in contact with the wood of the casing, but all the friction will occur upon the metal wearing-blocks *t*, and so prevent wear upon the casing.

Attached to the inner surface of the wooden ring *N'* is a conical wire-cloth cage or screen, *P'*, encircling the shaft *B* and projecting a short distance into the reel.

P² is a brush attached to and revolving with the shaft *B* inside of and in contact with the cage *P'* to brush the material around in contact with the wire-cloth, as hereinafter described.

Upon the shaft *I³*, outside of the pinion *I²*, with which the gear *I'* engages, is a chain-pulley, *T'*, connected by a chain, *T²*, with another chain-pulley, *T³*, on one of the conveyers, as *C'*, by which the latter is driven. The other conveyer may also be provided with a chain pulley, and the chain *T²*, arranged to run around both pulleys or gears, may be used to connect the conveyer-shafts, as shown in Fig. 1.

Outside the chain-pulley *T³*, on the shaft *I³*, is secured a gear-wheel, *U'*, adapted to engage a pinion, *U²*, on the shaft *B*. By this arrangement the revolution of the shaft *B* will be communicated to the shaft *I³* through the pinion *U²* and gear *U'*, and thence by the pinion *I²*, on the shaft *I³*, to the gear *I'* on the reel, and thus revolve the latter.

By the difference of size of the gears and pinions the shaft *B* and beater-cylinder will

be revolved much faster than the reel, but in the same direction. The shaft and beater-cylinder will usually be revolved about (200) two hundred times per minute, and the reel about (30) thirty or (40) forty times per minute.

V is a hand-hole leading into the cage *P'*, through which the material too coarse to pass through the wire-cloth may be removed.

The material which is intended to be passed through this machine is fed into the cage *P'* through the spout *M³*, and is there acted upon by the revolving brush *P²*, and the finer particles forced through the wire-cloth upon the beater-arms and reel. The rapidly-revolving beaters *b* catch the material and throw it with considerable force outward against the cloth cage on the reel. The finer particles are driven through the cloth and fall into the conveyers, and are thence carried away from the machine, while the coarser particles escape by the tail-spout.

The material which is usually passed through this class of machines often contains coarse particles of bran, chaff, &c., and by using the wire-cloth cage *P'* this coarser material is separated out and held back, thus avoiding the extra friction on the bolting-cloth of the reel necessary to carry this coarser material over the tail. By this means also the cloth of the reel is protected from a large amount of unnecessary wear and friction, and will consequently last much longer than where the preliminary separation is not made.

The action of the brush *P²* and cage *P'* also serves to break up the coarser particles into smaller pieces, and thus reduce the amount of work required of the reel.

The beater-strips *b* will be provided with perforations *w* to cut up any heavy stock which the beaters and reel-ribs fail to act upon, the holes forming just so many more sharp edges and angles to act upon and cut up the material.

The frame of the reel, as indicated, is all of iron, and will be very strong and substantial without increasing the weight to an injurious extent.

W is a rod running through the casing *A'* and armed with a wrapping of cloth, which rests upon the bolting-cloth-covered cylinder and wipes the adhering dust loose therefrom as the reel revolves beneath it.

A very important advantage gained by the adjustment of the reel and beater-cylinder together by the shell *K³* is that the tail-discharge through the slots *h* can thereby be easily controlled and regulated, as the more the reel is inclined of course the faster will be the discharge.

Having described my invention and set forth its merits, what I claim is—

1. In a centrifugal separator, the combination of the casing *A'*, shaft *B*, adjustably mounted in the said casing, the beater-cylinder, reel head-disk *H'*, formed with a projecting central bearing-ring, *H⁴*, gear-rim *I'*, and

flange n^2 , reel tail-disk H^2 , having discharge-slots $h\ h$, ribs $H^3\ H^3$, connecting the said head and tail disks, fixed disk M' , and packing-ring N' , substantially as and for the purpose herein set forth.

5. 2. The combination of the casing, the bolting-cloth, the reel consisting of the tail-disk H^2 , head-disk H' , and ribs $H^3\ H^3$, the fixed central plate or disk M' , the packing-ring N' , wire-cloth cage P' , attached thereto, shaft B , and brush P^2 , substantially as shown and described.

10. 3. The combination of the casing A' , the shaft B , the beater-cylinder, boxes $K^2\ K^7$, sleeve or shell K^3 , adjusting-screw K^8 , set-screws $d^1\ d^2\ d^3\ d^4$, tail-disk H^2 , having discharge-ports $h\ h$, head-disk H' , having gear I' and packing-ring N' , ribs $H^3\ H^3$, connecting said head and tail disks and having wooden strips in the 20 angles thereof, and means, substantially as described, whereby said reel-disks and ribs may be rotated in the same direction, but at a less

speed than said shaft and beater-cylinder are rotated.

4. In a centrifugal separator, a beater-cylinder comprising the shaft B , spiders $G^1\ G^2$, formed in two parts and clamped to the shaft B , and inclined beater-ribs $b\ b$, connecting the heads at their peripheries, substantially as described.

15. 5. The combination of a bolting-cloth-covered reel constructed with tail and head disks and longitudinal ribs connecting the disks, a fixed central plate, M' , provided with a packing-ring, N' , and shaft B , carrying the beater-cylinder, substantially as herein set forth.

In testimony whereof I have hereunto set my hand in presence of two subscribing witnesses.
